Primary Examiner — Ricky Pham(74) *Attorney, Agent, or Firm* — Price Heneveld LLP(57) **CLAIM**

The ornamental design for a food processing attachment, as shown and described.

DESCRIPTION

FIG. 1 is a top-front perspective view of a food processing attachment according our design;

FIG. 2 is a bottom-back perspective view thereof;

FIG. 3 is a back view thereof;

FIG. 4 is a front view thereof;

FIG. 5 is a right side view thereof;

FIG. 6 is a left side view thereof;

FIG. 7 is a top view thereof; and,

FIG. 8 is a bottom view thereof.

Broken lines are used to show features that are environmental only and form no part of the claimed design.

1 Claim, 6 Drawing Sheets(56)
